(57) **CLAIM**

The ornamental design for a flexible stand, as shown and
described.

DESCRIPTION

FIG. 1 is an upper perspective view of a flexible stand
according to our new design shown in a folded or retracted
position;

FIG. 2 is a front elevational view of the flexible stand in the
retracted position;

FIG. 3 is a rear elevational view of the flexible stand in the
retracted position;

FIG. 4 is a top plan view of the flexible stand in the retracted
position;

FIG. 5 is a bottom plan view of the flexible stand in the
retracted position;

FIG. 6 is a left side elevational view of the flexible stand in the
retracted position;

FIG. 7 is a right side elevational view of the flexible stand in the
retracted position;

FIG. 8 is a perspective view of the flexible stand in an
extended or in-use position;

FIG. 9 is a front elevational view of the flexible stand in the
extended position;

FIG. 10 is a rear elevational view of the flexible stand in the
extended position;

FIG. 11 is a top plan view of the flexible stand in the
extended position;

FIG. 12 is a bottom plan view of the flexible stand in the
extended position;

FIG. 13 is a left side elevational view of the flexible stand
in the extended position; and,

FIG. 14 is a right side elevational view of the flexible stand
in the extended position.

The broken line showing of an opening in the flexible stand
is for the purpose of illustrating portions of the article and
forms no part of the claim. The broken line showing of an
object being supported by the flexible stand in FIGS. 8-14 is
for the purpose of illustrating environmental structure and
forms no part of the claimed design.

1 Claim, 12 Drawing Sheets
